UNITED STATES PATENT OFFICE.

FREDERICK C. MCCLARY, OF WHITESBORO, NEW YORK.

DESIGN FOR A MEMBER FOR PLIERS OR SIMILAR INSTRUMENTS.

SPECIFICATION forming part of Design No. 34,077, dated February 12, 1901.

Application filed October 14, 1896. Serial No. 608,894. Term of patent 14 years.

To all whom it may concern:

Be it known that I, FREDERICK C. MCCLARY, a citizen of the United States, residing at Whitesboro, in the county of Oneida and State of New York, have invented and produced a new and useful Design for a Member for Pliers and Similar Instruments, of which the following is a specification.

The leading feature of my design consists in a body portion or joint of a plier member having a flat outer face with rectangular oppositely-extending ends in parallelism with one another, whereby the said end portions, together with the intervening section, form the half of a rectangular or box-like figure, the parallel extensions or ends referred to being joined by the said intervening section and which has oppositely-curved sides.

In the accompanying drawings, Figure 1 is a side view of a plier member made in accordance with my design, and Fig. 2 is a plan view of the same.

The body portion or joint A of the plier

member has the rectangular oppositely-extending offset end sections a a', having sides b b', which are in line or parallel with one another, as clearly shown in Fig. 1, said sections having the faces of their ends at right angles to said sides b b', so as that the said sections, together with the intervening connecting-section, form the half of a rectangular or box-like figure, and the said intervening section, which has its opposite sides a² a² curved, as shown in Fig. 1, joining the said end sections a a'. From the angular end section a extends the handle of the plier member, while from the other end section a' projects the plier jaw or point.

I claim—

The design for a plier member herein shown and described.

FREDERICK C. MCCLARY.

In presence of—

HUGH WHITE,
E. S. MATHEWS.
